UNITED STATES PATENT OFFICE.

CHARLES M. P. MONTBARBON, DECEASED, LATE OF NEUILLY, BY HENRI WAËL,
ADMINISTRATOR, OF LEVALLOIS-PERRET, FRANCE, AND GUSTAVE EMILE
CHÉDRU, OF LEVALLOIS-PERRET, FRANCE.

FRICITION-GEARING.

1,230,011.

Specification of Letters Patent. Patented June 12, 1917.

Application filed January 18, 1915. Serial No. 2,945.

To all whom it may concern:

Be it known that CHARLES MAURICE PHILIPPE MONTBARBON, deceased, formerly a citizen of the Republic of France, residing at Neuilly, France, and GUSTAVE EMILE CHÉDRU, a citizen of the Republic of France, residing at Levallois-Perret, Department of Seine, France, (HENRI WAËL, a citizen of the Republic of France, residing at Levallois-Perret, Department of the Seine, France, administrator of said CHARLES M. P. MONTBARBON,) have invented certain new and useful Improvements in Friction-Gearing, of which the following is a specification.

15 The present invention relates to friction gearing for motor cars, and more particularly to that type of gearing which comprises a disk and a friction wheel co-operative therewith.

20 The invention comprehends, briefly, the provision of means or mechanism for automatically imposing a gradually-increasing pressure upon the disk as the friction wheel approaches nearer toward the center thereof, so that the force of engagement or contact 25 between the two parts thus varies in accordance with the changes in their relative positions and, therefore, with the changes in speed.

30 An embodiment of the invention is illustrated in the accompanying drawing, whereof:—

Figure 1 is a fragmental, horizontal section of a motor car equipped with the improved gearing, the section being taken on line 1—1 of Fig. 2.

Fig. 2 is a part-sectional side elevation.

Fig. 3 is a detail section, taken on line 3—3 of Fig. 1.

40 Fig. 4 is an enlarged detail section, showing the mounting of a driving rod included in the invention.

According to the invention, which is shown and described as applied to a motor car, there is provided a forwardly-extending tube a' formed with an enlarged rear end a , to which is connected a pair of rearwardly-extending, curved branches a^2 and a^3 , the whole constituting a solid or rigid frame 45 which avoids vibration. This frame is secured to the chassis of the car at three points only, viz: at the free ends a^{20} and a^{30} of

the branches a^2 and a^3 , respectively, which are fastened directly to the side bars of the chassis, and at the free end a^{10} of the tube a' , 55 which is attached to one of the cross-bars thereof.

Within the tube a' is disposed a shaft b , which is inclosed by an intermediate hollow shaft or tube b^0 , the arrangement being such 60 that the parts b , b^0 are capable of a slight endwise movement in unison in said tube a' . The shaft b is connected at one end, by a universal joint c , with the crank shaft of the engine, and has a friction disk b' attached 65 to its other end, for engagement with a friction wheel d' , the latter being keyed for sliding movement on a shaft d , which is mounted in the ends of the branches a^2 and a^3 and is disposed perpendicularly to, and co-planar 70 with the shaft b . This shaft d is connected to drive the rear axle, (not shown) by a suitably chain and sprocket mechanism j , (Fig. 1).

To effect the movements of the friction 75 wheel d' along its shaft, a mechanism is provided, which comprises a two-armed lever e , pivoted at its apex on a vertical pin e' , fixed to the branch a^3 , and a control lever f . One arm of this lever e is connected by a rod e^2 80 to said friction wheel, while its other arm is connected by a rod e^3 to an arm f' , which is keyed to a transverse shaft or spindle f^2 , the latter having keyed thereon a sliding sleeve 85 f^3 to which the afore-mentioned control lever f is secured. As the friction wheel approaches the center of the disk b' , said disk is caused to bear against the friction wheel with gradually-increasing force, such action being obtained automatically through the 90 intermediary of suitable means or mechanism, connected up, as hereinafter described, to the shaft b , so as to move the latter toward said friction wheel.

The mechanism just referred to, preferably 95 embodies a two-armed lever, or its equivalent, one arm of which is connected to shift shaft b endwise, while the other arm is operatively associated with a device which exerts a constant pressure thereon, the point 100 at which such force or pressure is imposed varying in accordance with the movements of the friction wheel d' . In the construction illustrated, a spindle g is journaled

interiorly of tube a' , and has secured to it a fork g' , whose prongs engage between annular shoulders b^2 provided on tube b^0 , so that a rocking movement of spindle g will effect an endwise movement of said tube and, with it, shaft b , said fork thus forming one of the two arms of the lever above mentioned. The other arm of said lever is constituted by an arcuate rod g^2 , which is pivoted to the projecting end of the spindle g , said rod having a sliding engagement with the bifurcated upper portion h^3 of a driving rod h^2 . The body portion of this rod extends loosely into a casing h' , which is pivoted at its lower end on a pin h , carried by the tube a' , or by some other fixed part, said pin h being located concentrically with respect to the curved rod or arm g^2 . Within this casing h' , there is also arranged a downwardly-acting expansible coil spring h^5 , which encircles rod h^2 , and bears at its lower end against the enlarged lower end h^4 of the rod, and at its upper end against the upper wall of the casing, as shown in Fig. 4. The enlarged rod end h^4 just referred to, has a sliding fit within said casing, by reason of which fact the rod will be capable of an endwise sliding movement relative to the casing, and will tend to move downwardly therethrough, due to the downward pressure constantly imposed upon its said enlarged end by the expansion spring.

When the casing h' is in its rear position, represented in Fig. 2, *i. e.*, with the forked end h^3 of rod h^2 in juxtaposition to the spindle g , the downward pressure exerted by the aforesaid spring h^5 will be ineffective to depress rod h^2 , so as to produce rocking movement of the curved lever arm g^2 , since the leverage afforded by the latter is insufficient to overcome the weight of the shaft b and associated parts connected with said arm. But if the casing h' be swung forwardly, then the leverage afforded by arm g^2 will be correspondingly increased, with the result that the spring will be enabled to pull rod h^2 and arm g^2 downwardly, though the force actually exerted by the spring itself remains constant. The downward movement of arm g^2 causes a rocking movement of spindle g in a counter-clockwise direction, thereby causing fork g' , to rock in the same direction and, therefore, to move shaft b rearwardly, this movement of shaft b serving to press disk b' against the friction wheel d' , the pressure increasing as the downward movement of arm g^2 continues.

The forward swinging movement of casing h' is effected automatically, as previously stated, and is preferably obtained by pivotally connecting to said casing the forward end of a rod or link i , whose rear end is pivoted to an arm f^3 , which is keyed to the shaft or spindle f^2 and extends downwardly and rearwardly therefrom, as shown

in dotted lines in Fig. 2. Hence, when lever f is swung rearwardly to shift the friction wheel d toward the center of the disk b' , said arm f^3 will be caused to swing forwardly, and, in turn, will shift rod i forward, thereby effecting the desired movement of the casing h' . The aforesaid casing is preferably constructed in two parts, which are detachably and adjustably connected together, so as to permit the insertion of the driving rod h^2 and its expansion spring h^5 , and, also, to enable the tension of the spring to be regulated.

The return or forward movement of the shaft b , is preferably effected by means of a pedal l , whose spindle or shaft is connected by a vertical link l' with the front end of the arcuate lever arm g^2 . In consequence of this arrangement, depression of said pedal will raise link l' , as will be understood, thereby swinging arm g^2 upwardly, with the result that spindle g is rotated in a clockwise direction, its fork g' being thereby caused to shift shaft b forwardly, such movement disengaging disk b' from friction wheel d' and, therefore, throwing the transmission out of gear. This pedal mechanism is also utilized to lock the transmission out of gear, for which purpose the pedal is provided with an extension l^2 that coacts with a sliding cross-bar l , (Figs. 1 and 3). The latter is connected by a rod or link l' , with the long forward arm of a lever l^2 , that is pivoted at l^0 to the chassis, the short, rear arm of the lever being pivoted to the sliding sleeve l^3 keyed to the shaft or spindle f^2 , to which sleeve the lever f is fixed. Hence, it follows that when the pedal has been depressed, to throw out the transmission, and the lever f is moved laterally in the proper direction, the movement of said lever will produce a slight sliding movement of sleeve l^3 along shaft f^2 , thereby rocking lever l^2 , with the result that the bar l will be shifted endwise beneath the extension l^2 of the pedal, thus retaining the pedal in actuated position. When lever f is again operated to throw the transmission into gear, the cross-bar l will be withdrawn from beneath said extension l^2 and the pedal will be returned to normal position by the downward movement of lever arm g^2 , effected as above described. It is thus possible to throw the transmission into and out of gear at any speed.

The driving chain j is disposed within a case j' , (Fig. 1), which has a pivotal mounting at one end on the rear driving axle, (not shown), and is mounted at the other end on an eccentric j^2 , the latter having, in turn, a ball-and-socket mounting on a tubular support a^{200} , constituted by an inward extension of the branch a^2 . Such arrangement enables the end thrust of the axle to be transmitted to the aforesaid support, and

at the same time, permits the floating movements of the axle relative to shaft d to take place without varying the distance between the two sprockets over which chain j passes, the eccentric also permitting said chain to be tightened when necessary.

The invention is not intended to be restricted to the precise construction shown and described, since modifications and changes may obviously be made within the scope of the appended claims.

What we claim as our invention and desire to secure by Letters Patent is:—

1. Friction gearing comprising driving and driven members, means for moving said members into frictional engagement, and a device exerting a constant uniform tension on said means to insure frictional engagement between said members, said device being movable relative to said means, whereby the force of contact between said members may be increased and diminished without varying the tension exerted on said means.

2. Friction gearing comprising driving and driven members, a pivoted lever having connection with one of said members for moving said members into frictional engagement, and means exerting constant force on said lever and shiftable along the length of said lever, whereby the force of contact between said members may be varied.

3. Friction gearing comprising a disk and a wheel, the latter being shiftable radially relative to the disk, a pivoted lever having connection with said disk for moving the same into frictional engagement with the wheel, and means exerting a constant force on said lever and shiftable along the length of the lever, whereby the force of contact between said disk and wheel may be varied.

4. Friction gearing comprising a disk and a wheel, the latter being shiftable radially relative to the disk, a pivoted lever having connection with said disk for moving the same into frictional engagement with the wheel, means exerting a constant force on said lever and shiftable along the length of the lever, and means for automatically shifting said force exerting means when the wheel approaches and recedes from the center of the disk, whereby the force of contact between the disk and wheel is increased and diminished.

5. Friction gearing comprising a disk and a wheel, the latter being shiftable radially relative to the disk, a pivoted lever having connection with said disk for moving the same into frictional engagement with the wheel, means exerting a constant force on said lever and shiftable along the length of the lever, and a connection between said wheel and force exerting means, whereby the force of contact between the disk and

wheel is varied as the latter is shifted relative to the disk.

6. Friction gearing comprising a disk and wheel, the latter being shiftable radially relative to the disk, a pivoted lever having connection with said disk for moving the same into frictional engagement with the wheel, means exerting a constant force on said lever and shiftable along the length of the lever, a connection between said wheel and force exerting means whereby the force of contact between the disk and wheel is varied as the latter is shifted relative to the disk, and manually-controlled means for moving said disk and wheel out of engagement.

7. Friction gearing comprising driving and driven members, a pivoted lever having connection with one of said members for moving said members into frictional engagement, means exerting constant force on said lever and shiftable along the length of said lever, whereby the force of contact between said members may be varied, and manually controlled means for moving said members out of engagement.

8. Friction gearing comprising driving and driven members, a curved lever having a fixed pivot and movable for shifting said driving member into engagement with the driven member, and pivoted means mounted to oscillate about the center of the arc formed by the curved lever and adapted to constantly exert force upon said lever, whereby the force of contact between said members may be varied by the oscillation of said force exerting means.

9. Friction gearing comprising driving and driven members, the driven member being shiftable relative to the driving member, a curved lever having a fixed pivot and movable for shifting said driving member into engagement with the driven member, pivoted means mounted to oscillate about the center of the arc formed by the curved lever and adapted to constantly exert force upon the latter, and a connection between said driven member and force exerting means to operate the latter from the former, whereby the force of contact between said members may be varied.

10. Friction gearing comprising driving and driven members, shifting means for moving said members into and out of frictional engagement, a device exerting a constant and uniform force on said shifting means to normally insure frictional engagement between said members, said device being movable relative to said shifting means, whereby the force of contact between said members may be increased and diminished, without varying the tension exerted upon said shifting means, and means for locking said shifting means when said members are moved out of frictional engagement.

11. Friction gearing comprising driving and driven members, shifting means for moving said members into and out of frictional engagement, a device exerting a constant force on said shifting means to normally insure frictional engagement between said members, means for controlling the force of contact between said members, and a locking device controlled by the operation of said controlling means for locking said shifting means when said members are moved out of frictional engagement.

12. Friction gearing comprising driving and driven members, shifting means for moving said members into and out of frictional engagement, a device exerting a constant force on said shifting means to normally insure frictional engagement between said members, means for controlling the force of contact between said members, and a locking device controlled by the operation of said controlling means for locking said shifting means when said members are moved out of frictional engagement and for releasing said shifting means when said members are moved into frictional engagement.

13. In a device of the character described,

the combination of a frame having one end formed with oppositely projecting arms, a shaft supported in the outer ends of said arms and extending substantially transversely of the frame, a second shaft longitudinally journaled in the frame, a friction disk mounted on one end of said second shaft, a friction wheel slidably mounted on said first-mentioned shaft for frictional engagement with the disk, said second shaft being slideable endwise in said frame, whereby said friction members may be moved out of engagement, means for normally exerting pressure on said shaft to effect the engagement of said disk and wheel and means for varying the force of contact between said disk and wheel according to the position of said wheel upon its shaft.

In testimony whereof we have hereunto set our hands in presence of two subscribing witnesses.

HENRI WAËL,

Administrator.

GUSTAVE EMILE CHÉDRU.
